JAMES B. CLARK, OF PLANTSVILLE, CONNECTICUT.

Letters Patent No. 67.024, dated July 23, 1867.

IMPROVEMENT IN THE METHOD OF MAKING SOLID BLANKS FOR WAGON-SHACKLE.

The Schedule referred to in these Letters Patent and making part of the same.

TO ALL WHOM IT MAY CONCERN:

Be it known that I, JAMES B. CLARK, of Plantsville, in the county of Hartford, and State of Connecticut, have invented a new and improved Manner of Forming Solid Blanks for Wagon-Shaft Shackle; and I do hereby declare that the following is a full, clear, and exact description thereof, which will enable others skilled in the art to which my invention appertains to make and use the same, reference being had to the accompanying drawings, forming part of this specification, in which—

Figure 1 is a plan or top view of a bar of iron from which I make the blank.

Figure 2 is a similar view of the bar, showing the cuts or slots which indicate the lines of separation of the blanks.

Figure 3 is a plan or top view of a blank separated from the bar.

Figure 4 is a similar view of a completed blank.

Similar letters of reference indicate like parts.

The object of this invention is to form the solid blank for wagon-shaft shackle from one bar of iron in such a manner that, although the blank is cross-shaped, having four arms which meet at right angles, the grain of the iron should run parallel with the direction of each arm in each arm, and that the said blank should furthermore be made of one single piece of metal. Heretofore such blanks were either formed by welding two bars together, or a bar of iron was formed into the necessary shape between dies, the arms being pressed out from the body; thereby the direction of the grain was interrupted in the arms, and the strength of the article consequently reduced. By my method all these difficulties are overcome, as I make a complete and strong article with the least amount of power and labor.

In carrying out my invention, I bend an iron bar, A, by any suitable means, into the shape indicated in fig. 1; that is to say, I bend the portions B of the bar alternately to one and to the other side of a line drawn longitudinally through the centre of the bar, as indicated in fig. 1, or, in other words, the portions B are bent eccentrically to the axis of the bar, the different portions thus divided off by bending the bar in the aforesaid manner being connected with each other by strips α , at an angle of about forty-five degrees. Instead of bending the bar A, it may be swaged between rolls or otherwise, in such a manner that the grain of the iron shall be parallel with the sides of the bar. The bar which has been thus shaped is divided in sections, and each section slotted, as indicated by the lines d e f , the latter running transversely from the cut or slot d in a direction perpendicular to those of the arm b , to the respective edges of the bar, as is clearly shown in fig. 2, each piece, when separated from the other, forming one blank of the shape represented in fig. 3. By these cuts or slots, the body c c' and the arms b b' may be formed in each blank, and before said blanks are separated from each other. In forming the slots two cutters are employed, one cutting the longitudinal grooves or slots, and the other placed at right angles thereto, simultaneously cutting the transverse slots e . The slot f is formed by any ordinary cutter, and is the last point separated from the bar in forming the blank shown in fig. 3. The longer arm b of one blank touches the shorter arm b' of the next blank, and the part c of one body touches the part c' of the other body. These pieces C C, when separated, may be, by any suitable process or in any suitable manner, bent or swaged into the proper shape; that is to say, the arms b and b' may be bent at right angles to the body c c' , as is shown in fig. 4, and a complete solid blank for wagon-shaft shackle is thus formed, in which the grain of the metal is made to run parallel, or nearly so, with the direction of each arm b b' and c c' .

Having thus described my invention, what I claim therein as new, and desire to secure by Letters Patent, is—

The method of making and forming the solid blanks for wagon-shaft shackle of one piece of metal, the grain thereof running parallel, or nearly so, with the direction of each arm, substantially as set forth.

JAMES B. CLARK.
